UNITED STATES PATENT OFFICE.

JAMES NEWHOUSE, OF JERSEY CITY, NEW JERSEY.

SPRING-BED.

SPECIFICATION forming part of Letters Patent No. 320,493, dated June 23, 1885.

Application filed January 29, 1885. (No model.)

To all whom it may concern:

Be it known that I, JAMES NEWHOUSE, a citizen of the United States, and a resident of Jersey City, in the county of Hudson and State 5 of New Jersey, have invented certain new and useful Improvements in Spring-Beds, of which the following is a specification.

My invention relates to an improved spring-bed; and it consists in mounting the springs 10 upon parallel slats and in connecting these slats by means of pivoted links, as hereinafter more fully set forth, so that they will at all times be parallel and the springs thereon equally distributed over the upper surface of 15 the bed, said links being so pivoted as to permit the bed to be widened or narrowed at pleasure, allowing it to be made very narrow and compact for handling and shipping without bending its parts or entangling the springs.

20 My invention furthermore consists in an improved link for connecting the springs the one to the other, said links adapted to present a smooth even surface to the bed-clothes placed thereon and to prevent undue wear thereof.

25 In the accompanying drawings, Figure 1 is a top view of my improved spring-bed. Fig. 2 is a diagram view showing method of operating the same. Fig. 3 is an end view of bed as shown in Fig. 1. Fig. 4 is a detached view 30 of two of the springs, showing the link-connection or brace therefor.

My improved device is constructed as follows: A A A are a series of slats, preferably either five or seven in number and made of 35 sheet metal, and upon these slats are mounted a series of conical springs, B, so spaced upon the several slats as that they will stand in diagonal rows when the bed is opened, as shown in Fig. 1. Each two adjacent slats are joined 40 together at two or more points of their length by pivoted links C, which are themselves divided into two parts, c c, pivoted together, as at C'. The pivotal points C' of the connections

C between each pair of slats are connected by a rigid rod, D, by means of which said connections are operated and made to move in unison. 45

A longitudinal movement of the rod D between their respective pairs of slats A will cause the links C to operate and draw the slats 50 together, as shown in Fig. 2, or the reverse.

The springs B, mounted upon the slats, are connected in diagonal rows by means of link-plates E E, secured to the upper coil of the springs and adapted to present a broad flat 55 surface to the bed-clothes placed upon the springs, and there are two such links between each pair of springs coupled by a short link, e, which will allow each pair of link-plates E to fold together beneath the level of the 60 springs when the slats are closed together, as shown in Fig. 2.

The springs upon the two outer slats of the bed are braced and kept in line by means of a metallic strip, F, secured to the upper surface of the springs, and their bracing strips are re-enforced, each by two or more diagonal braces, G, secured by a pivotal connection 65 to the second slat from each side of the bed, and having a lateral slot near their outer end 70 to engage a pin or lug on the lower side of the strip F.

Having described my invention, what I claim is—

In an adjustable spring-bed, the combination 75 of the slats A, conical springs B, pivotal links C, rigid rods D, link-plates E, short links e, metallic strips F, and diagonal braces G.

Signed at New York, in the county of New York and State of New York, this 26th day 80 of January, A. D. 1885.

JAMES NEWHOUSE.
